PACKAGE WINDING MACHINE

John O. McKean, Westfield, Mass., assignor to
 Foster Machine Company, Westfield, Mass., a
 corporation of Massachusetts

Application December 10, 1930
 Serial No. 501,286

32 Claims. (Cl. 242—18)

This invention is directed to package winding machines of that type in which the packages are wound by their frictional surface contact with driving rolls. The object of my invention 5 is to provide a novel and simple winding mechanism which will effectually break up the ribbon wind on the package, i. e., the tendency of the yarn to lay one turn upon a preceding turn thereby causing undesirable lumps or protuberances to be produced in the wound package.

My invention comprises, generally, a package winding mechanism in which either the winding roll shaft or the traverse guide actuating cam shaft is driven at a constant speed, a resilient 15 driving connection being provided between the two shafts and a brake also being employed for intermittently reducing the speed of the cam shaft or the winding roll shaft, as the case may be, against the tension of the resilient driving connection, said brake being perfectly operated 20 through a speed reducing mechanism by the means which drives the constant speed shaft; it being understood that when the brake is released its shaft will speed up due to the increased tension or stored up energy of the 25 resilient driving connection, until the shaft reaches its normal speed with respect to that of the constant speed shaft.

Two practical embodiments of my invention 30 are represented in the accompanying drawings, in which:

Fig. 1 represents a detail end view of a winding machine with one embodiment of my improved winding mechanism applied thereto 35 wherein the winding roll shaft is driven at a constant speed and the traverse guide actuating cam shaft is resiliently driven by the winding roll shaft at a variable speed;

Fig. 2 represents a detail side view of the 40 same;

Fig. 3 represents a detail longitudinal section showing the resilient driving connection between the winding roll shaft and the traverse guide actuating cam shaft;

Fig. 4 represents a detail end view of a winding machine with an alternate embodiment of my improved winding mechanism applied thereto, wherein the cam shaft is driven at a constant speed and the winding roll shaft at a 50 variable speed;

Fig. 5 represents a detail side view of the same; and

Fig. 6 represents a detail longitudinal section showing the resilient driving connection between the cam shaft and the winding roll shaft.

While two winding mechanisms are shown in each embodiment of my invention one only in each embodiment will be specifically described as they are similar in construction, arrangement and operation. In both embodiments the winding machine frame is denoted by 1 and in this frame are rotatably mounted the winding roll shaft 2 and the traverse guide actuating cam shaft 3. The position of the package 4 being wound is indicated in dotted lines. The winding roll is denoted by 5, the traverse guide by 6 and its actuating cam by 7.

In the form shown in Figs. 1 to 3 inclusive the winding roll shaft 2 is driven at a constant speed by any suitable means, such, for instance, as an electric motor 8 which is shown as driving the said shaft through the belt and pulley connection 9 and 10, 11.

The resilient driving connection between the winding roll shaft 2 and the traverse guide actuating cam shaft 3 is shown as comprising the following elements: A gear 12 fast on the winding roll shaft 2 drives a gear 13 whose sleeve 14 is loosely mounted on the traverse guide actuating cam shaft 3. A spring tension driving connection is provided between the driven gear 13 and the cam shaft 3 by means of a coil spring 15, one end of which is attached at 16 to the sleeve 14 and the other end of which is attached at 17 to a sleeve 18 secured at 19 on the shaft 3. Suitable washers 20 and 21 may be interposed between the opposite ends of the sleeve 14 and the sleeve 18 and collar 22 respectively, which collar 22 is secured at 23 on the cam shaft 3.

The brake for intermittently retarding and speeding up the cam shaft 3 to break up the ribbon wind on the package, is shown as operated by the motor drive for the winding roll shaft through a speed reducing mechanism as follows: The motor 8 is shown as having a belt and pulley driving connection 24 and 25, 26 with a longitudinally disposed worm shaft 27 mounted in suitable bearings in a bracket 28 carried by the main frame 1. In the present instance the pulley 26 is loosely mounted on the worm shaft 27 and has a one-way driving connection therewith through a pawl 29 which engages a ratchet 30 secured to said shaft. This worm shaft 27 is provided with a worm 31 which meshes with a gear 32 on a cross shaft 33 also mounted in suitable bearings in the bracket 28. One end of this cross shaft 33 is provided with an eccentric pin 34 which rides in an elongated slot 35 in one arm 36 of a rock lever fast on a cross shaft 37, the other arm 38 of which lever

is connected by a vertical rod 39 with one arm . with respect to the other and means for intermittently actuating said retarding means. 5
40 of a brake lever fast on a longitudinally disposed shaft 41, the other arms 42 of which brake lever is provided with a suitable brake shoe 43, arranged to be brought into and out of frictional engagement with a drum 44 fast on the cam shaft 3.

The free end of the brake lever arm 40 is held pressed against an adjustable stop 45 on the vertical connecting rod 39 by means of a coil spring 46 interposed between said arm 40 and another adjustable stop 47 on said rod. 10

The speed reducing mechanism may be employed for the winding mechanisms on both 15 sides of the machine by providing the other motor 8 with a belt and pulley driving connection 48 and 49, 50 with the worm shaft 27, the pulley 50 being loosely mounted on the worm shaft 27 and having a one-way driving connection therewith through a pawl 51 which engages the ratchet 30 fast on the said shaft. It will be understood that the cross shaft 37 will carry the lever arm 38 of the brake connection for the other winding mechanism. 20

25 In the alternative form shown in Figs. 4, 5 and 6 the cam shaft 3 is driven at a constant speed and the winding roll shaft at a variable speed. In this form the electric motor 8 drives the cam shaft at a constant speed through the belt and pulley driving connection 9 and 10, 11, the pulley 11 being fast on the cam shaft in this instance instead of fast on the winding roll shaft as in the first described form. 30

35 In this alternative form the resilient driving connection between the cam shaft and the winding roll shaft is reversed, the driving gear 12 being fast on the cam shaft, the driven gear 13 and its sleeve being loosely mounted on the winding roll shaft and the coil spring 15 yielding connecting the sleeve with the winding roll shaft. 40

Also, in this alternative form the brake drum 44 with which the brake is arranged to be brought into and out of frictional contact, is 45 fast on the winding roll shaft instead of on the cam shaft.

The remaining parts of this alternative form are arranged and operated as in the first described form shown in Figs. 1, 2 and 3 and therefore they will not be again specifically described. 50

From the above description it will be seen that I have provided a very simple and effective means for effectually breaking up the ribbon wind on a package by introducing a resilient driving connection between the winding roll shaft and the traverse guide actuating cam shaft, together with a brake for intermittently retarding and speeding up the cam shaft or the winding roll shaft, as the case may be, it being understood that the timing and extent of the variable speed may be readily adjusted to suit different conditions. 55

It is evident that various changes may be resorted to in the construction, form and arrangement of the several parts without departing from the spirit and scope of my invention, and hence I do not intend to be limited to the particular embodiments herein shown and described, but

70 What I claim is:—

1. In a winding machine, a package winding roll, a winding roll shaft, a traverse guide, a traverse guide actuating cam shaft, a resilient driving connection between the two shafts, 75 means for retarding the rotation of one shaft

is connected by a vertical rod 39 with one arm . with respect to the other and means for intermittently actuating said retarding means. 80

2. In a winding machine, a package winding roll, a winding roll shaft, a traverse guide, a traverse guide actuating cam shaft, a resilient driving connection between the two shafts comprising a driving gear fast on one shaft, a driven gear loose on the other shaft and a tension spring connecting the driven gear with its shaft, means for retarding the rotation of said other shaft and means for intermittently actuating said retarding means. 85

3. In a winding machine, a package winding roll, a winding roll shaft, a traverse guide, a traverse guide actuating cam shaft and means for causing the cam shaft to alternately slow down and speed up, said means including a resilient driving connection between the two shafts, a brake for the cam shaft, and means for intermittently actuating said brake. 90

4. In a winding machine, a traverse guide, a traverse guide actuating cam shaft, a package winding roll, a winding roll shaft and means for causing the winding roll shaft to alternately slow down and speed up, said means including a resilient driving connection between the two shafts, a brake for the winding roll shaft, and means for intermittently actuating said brake. 95

5. In a winding machine, a package winding roll, a winding roll shaft, driving means therefor, a traverse guide, a traverse guide actuating cam shaft and means for causing the cam shaft to alternately slow down and speed up, said means including a resilient driving connection between the two shafts, a brake for the cam shaft and means operated by said driving means for intermittently actuating said brake. 100

6. In a winding machine, a traverse guide, a traverse guide actuating cam shaft, driving means therefor, a package winding roll, a winding roll shaft and means for causing the winding roll shaft to alternately slow down and speed up, said means including a resilient driving connection between the two shafts, a brake for the winding roll shaft and means operated by said driving means for intermittently actuating said brake. 115

7. In a winding machine, a package winding roll, a winding roll shaft, driving means therefor, a traverse guide, a traverse guide actuating cam shaft and means for causing the cam shaft to alternately slow down and speed up, said means including a resilient driving connection between the two shafts, a brake for the cam shaft and means comprising a speed reducing mechanism operated by said driving means for intermittently actuating said brake. 125

8. In a winding machine, a traverse guide, a traverse guide actuating cam shaft, driving means therefor, a package winding roll, a winding roll shaft and means for causing the winding roll shaft to alternately slow down and speed up, said means including a resilient driving connection between the two shafts, a brake for the winding roll shaft and means comprising a speed reducing mechanism operated by said driving means for intermittently actuating said brake. 135

9. In a winding machine, a package winding roll, a winding roll shaft, driving means therefor, a traverse guide, a traverse guide actuating cam shaft and means for causing the cam shaft to alternately slow down and speed up, said means comprising a resilient driving connection between the two shafts, a drake drum on the 145

- cam shaft and a brake arranged to be brought into engagement with the drum, and means operated by said driving means for intermittently actuating said brake.
- 5 10. In a winding machine, a traverse guide, a traverse guide actuating cam shaft, driving means therefor, a package winding roll, a winding roll shaft and means for causing the winding roll shaft to alternately slow down and speed up, said means comprising a resilient driving connection between the two shafts, a brake drum on the winding roll shaft and a brake arranged to be brought into engagement with the drum, and means operated by said driving means for intermittently actuating said brake. 80
- 10 11. In a winding machine, a package winding roll, a winding roll shaft, driving means therefor, a traverse guide, a traverse guide actuating cam shaft and means for causing the cam shaft to alternately slow down and speed up, said means comprising a resilient driving connection between the two shafts, a brake drum on the cam shaft and a brake arranged to be brought into engagement with the drum, and means comprising a speed reducing mechanism operated by said driving means for intermittently actuating said brake. 85
- 15 12. In a winding machine, a traverse guide, a traverse guide actuating cam shaft, driving means therefor, a winding roll, a winding roll shaft and means for causing the winding roll shaft to alternately slow down and speed up, said means comprising a resilient driving connection between the two shafts, a brake drum on the winding roll shaft and a brake arranged to be brought into engagement with the drum, and means comprising a speed reducing mechanism operated by said driving means for intermittently actuating said brake. 90
- 20 13. In a winding machine, a package winding roll, a winding roll shaft, driving means therefor, a traverse guide, a traverse guide actuating cam shaft, a resilient driving connection between the two shafts, a brake drum on the winding roll shaft and a brake arranged to be brought into engagement with the drum, and means comprising a speed reducing mechanism operated by said driving means for intermittently actuating said brake. 95
- 25 14. In a winding machine, a traverse guide, a traverse guide actuating cam shaft, driving means therefor, a package winding roll, a winding roll shaft and means for causing the winding roll shaft to alternately slow down and speed up, said means comprising a resilient driving connection between the two shafts, a brake drum on the cam shaft and a brake arranged to be brought into engagement with the drum, and means comprising a speed reducing mechanism operated by said driving means for intermittently actuating said brake. 100
- 30 15. In a winding machine, a package winding roll, a winding roll shaft, driving means therefor, a traverse guide, a traverse guide actuating cam shaft, a resilient driving connection between the two shafts, a brake for the cam shaft, and means for intermittently actuating said brake comprising a speed reducing mechanism connected to the brake and a one-way driving connection between the winding roll shaft driving means and the speed reducing mechanism. 105
- 35 16. In a winding machine, a package winding roll, a winding roll shaft, driving means therefor, a traverse guide, a traverse guide actuating cam shaft, a resilient driving connection between the two shafts, a brake for the cam shaft, and means for intermittently actuating said brake comprising a speed reducing mechanism connected to the brake and a one-way driving connection between the winding roll shaft driving means and the speed reducing mechanism. 110
- 40 17. In a winding machine, package winding mechanisms, each comprising a winding roll, a winding roll shaft, means for driving it, a traverse guide, a traverse guide actuating cam shaft, a resilient driving connection between the two shafts and a brake for the cam shaft and means for intermittently actuating the brakes comprising a common speed reducing mechanism operatively connected to the brakes and one way driving connections between the winding roll shaft driving means and the speed reducing mechanism. 115
- 45 18. In a winding machine, package winding mechanisms, each comprising a traverse guide, a traverse guide actuating cam shaft, means for driving it, a winding roll, a winding roll shaft, a resilient driving connection between the two shafts and a brake for the winding roll shaft and means for intermittently actuating the brakes comprising a common speed reducing mechanism operatively connected to the brakes and one-way driving connections between the cam shaft driving means and the speed reducing mechanism. 120
- 50 19. In a winding machine, package winding mechanisms, each comprising a winding roll, a winding roll shaft, a motor for driving it, a traverse guide, a traverse guide actuating cam shaft, a resilient driving connection between the two shafts and a brake for the cam shaft and means for intermittently actuating the brakes comprising a common speed reducing mechanism operatively connected to the brakes and one-way driving connections between the motors and the speed reducing mechanism. 125
- 55 20. In a winding machine, package winding mechanisms, each comprising a traverse guide, a traverse guide actuating cam shaft, a motor for driving it, a winding roll, a winding roll shaft, a resilient driving connection between the two shafts and a brake for the winding roll shaft and means for intermittently actuating the brakes comprising a common speed reducing mechanism operatively connected to the brakes and one-way driving connections between the motors and the speed reducing mechanism. 130
- 60 21. In a winding machine, a package winding roll, a constant speed winding roll shaft, a traverse guide, a traverse guide actuating cam shaft, a resilient driving connection between the two shafts, means for retarding the rotation of the cam shaft with respect to the winding roll shaft, and means for intermittently actuating said retarding means. 135
- 65 22. In a winding machine, a traverse guide, a constant speed traverse guide actuating cam shaft, a package winding roll, a winding roll shaft, a resilient driving connection between the two shafts, means for retarding the rotation of the winding roll shaft with respect to the cam shaft and means for intermittently actuating said retarding means. 140
- 70 23. In a winding machine, a package winding roll, a constant speed winding roll shaft, a traverse guide, a traverse guide actuating cam shaft, a resilient driving connection between the two shafts, a brake, and means operable to cause 145
- 75 16. In a winding machine, a traverse guide, a traverse guide actuating cam shaft, a motor for driving it, a package winding roll, a winding

the brake to intermittently reduce the speed of the cam shaft.

24. In a winding machine, a traverse guide, a constant speed traverse guide actuating cam shaft, a package winding roll, a winding roll shaft, a resilient driving connection between the two shafts, a brake, and means operable to cause the brake to intermittently reduce the speed of the winding roll shaft.

10 25. In a winding machine, a package winding roll, a winding roll shaft, driving means for the winding roll shaft, a traverse guide, a traverse guide actuating cam shaft, a resilient driving connection between the two shafts, a brake for the cam shaft, and means operated by said driving means to cause the brake to act intermittently.

20 26. In a winding machine, a traverse guide, a traverse guide actuating cam shaft, driving means for the cam shaft, a package winding roll, a winding roll shaft, a resilient driving connection between the two shafts, a brake for the winding roll shaft, and means operated by said driving means to cause the brake to act intermittently.

30 27. In a winding machine, a package winding roll, a winding roll shaft, driving means for the winding roll shaft, a traverse guide, a traverse guide actuating cam shaft, a resilient driving connection between the two shafts, a brake for the cam shaft, and means operated by the driving means to cause the brake to act intermittently, said means including a speed reducing mechanism.

35 28. In a winding machine, a traverse guide, a traverse guide actuating cam shaft, a driving means for the cam shaft, a package winding roll, a winding roll shaft, a resilient driving connection between the two shafts, a brake for the winding roll shaft, and means operated by the driving means to cause the brake to act inter-

mittently, said means including a speed reducing mechanism.

29. In a winding machine, a package winding roll, a constant speed winding roll shaft, a traverse guide, a traverse guide actuating cam shaft, and a resilient driving connection between the two shafts comprising a driving gear fast on the winding roll shaft, a driven gear loose on the cam shaft and a tension spring connecting the cam shaft gear with the cam shaft, means for retarding the rotation of the cam shaft and means for intermittently actuating said retarding means.

80 30. In a winding machine, a traverse guide, a constant speed traverse guide actuating cam shaft, a package winding roll, a winding roll shaft, and a resilient driving connection between the two shafts comprising a driving gear fast on the cam shaft, a driven gear loose on the winding roll shaft and a tension spring connecting the winding roll shaft gear with the winding roll, means for retarding the rotation of the winding roll shaft and means for intermittently actuating said retarding means.

90 31. In a winding machine, a package winding roll, a winding roll shaft, a motor for driving it, a traverse guide, a traverse guide actuating cam shaft, a resilient driving connection between the two shafts, a brake for the cam shaft, and means including a continuously operating speed reducing mechanism driven by the motor for intermittently actuating the brake.

105 32. In a winding machine, a traverse guide, a traverse guide actuating cam shaft, a motor for driving it, a package winding roll, a winding roll shaft, a resilient driving connection between the two shafts, a brake for the winding roll shaft, and means including a continuously operating speed reducing mechanism driven by the motor for intermittently actuating the brake.
